ALOIS FEYERTAG, OF VIENNA, AUSTRIA, ASSIGNOR TO THE FIRM STEFAN GÖTZ & SOHNE KOMMANDIT GESELLSCHAFT, OF VIENNA, AUSTRIA

AUTOMATIC WARNING SIGNAL FOR RAILWAY CROSSINGS AND THE LIKE

Application filed August 25, 1927, Serial No. 215,436, and in Austria August 30, 1926.

This invention concerns an automatic warning-signal installation for railways and is particularly intended for highway crossings. One object of the invention is to provide a signalling apparatus suitable for single line railway track or tracks which are traversed in both directions, a signal being operated by the apparatus on the approach of any train towards the crossing from either direction.

The problem to be solved with such apparatus is that of causing the signal to be operated without regard to which direction the train is traversing the line section and of rendering the signal ineffective after the highway crossing has been passed over. Since there must be an operating device to be actuated by the train, for instance an insulated rail, a magnet generator or the like, for each direction, said device must not actuate the signal every time it is traversed; on the contrary the signal actuation should only take place when the train passes over the first distant operating device, which is situated on the approach side of the crossing.

The invention relates to an arrangement which enables the problem to be solved by means of simple circuits and by employing merely a single actuating device for each direction of travel, the warning signal being operated by the passing of a train over an actuating device located on the approach side of the crossing, and being put out of action when the train passes over the crossing, renewed operation of the warning signal being prevented when the train passes over the distant operating device located beyond the crossing.

According to the invention the switching of the circuits and the performance of a succession of operations during the passage of a train are controlled by contact arrangements which are actuated by a common actuating device and also by individual actuating devices. A succession of combinations of positions thus produced creates the necessary direction-selectivity of the apparatus whereby once the direction is settled by a train passing over the operating devices arranged on the track, the predetermined succession of switch-

ing movements necessary for the operations mentioned and the re-setting of the apparatus for further operation by a train travelling in either direction are automatically performed.

The apparatus necessary for the actuation of the contact arrangement consists of a control relay which serves for the individual control of each contact device and is operated by the particular distant operating device first traversed. Each of these relays is provided with a device for making a circuit which maintains the relay in a state of excitation during the passage of a train, even although the original circuit is interrupted by the excitation of the relay.

The actuating arrangement common to both contact devices is arranged at the highway crossing itself and consists of an electrically or mechanically controlled arm which embraces the two contact devices in common and is able to bring them into a definite position. Furthermore, the arrangement is such that, after displacement has occurred, there is an automatic return of that contact device associated with the distant control device which is passed over by the train after leaving the crossing.

In the accompanying drawing:

Fig. 1 is a diagram of one example of a complete installation in accordance with this invention.

Fig. 2 is a cross section to a larger scale showing means at a highway crossing for actuating the contact arrangements illustrated in Fig. 1.

Fig. 3 shows a modified arrangement of the means located at the highway crossing.

Fig. 4 illustrates a further element employed, when operating with magnets in place of batteries and insulated rails.

Referring to Fig. 1, it will be seen that in one of the rails of a single line track there are insulated rail sections J_1 and J_2 situated at a distance at respective sides of a highway crossing N . These insulated rail sections are connected with the control apparatus of the warning signal at the crossing as hereinafter described, the said apparatus comprising a battery or current generator B . The other rail of the track is connected with

one pole of the battery and serves as a common negative or return.

The control apparatus comprises two relay sets indicated generally by the reference characters R_1 and R_2 . The set R_1 comprises 5 two magnets m_1 m_2 and the set R_2 comprises two magnets m_3 and m_4 . The magnets m_1 m_2 have a common armature r_1 and the magnets m_3 m_4 have a common armature r_2 . These 10 armatures are shown pivoted and in operative connection with pawls or detents s_1 s_2 .

In the set R_1 there is a vertically sliding rod K_1 fitted with a tooth Z_1 and in the set R_2 there is a similar rod K_2 with a tooth Z_2 , the 15 teeth of these rods being adapted for being engaged by respective pawls s_1 s_2 when the rods are lifted. Naturally the rods K_1 K_2 need not be vertical, as the only requirement 20 is that they should be movable longitudinally and have a constant tendency to return to a starting position.

The rods K_1 and K_2 are in operative relation with a common actuating device C located at the highway crossing. When the 25 device C is operated it shifts the rods longitudinally so that the pawls s_1 s_2 may automatically engage the teeth Z_1 Z_2 and retain the rods in the position in which the rod K_2 is seen in Fig. 1.

The actuating device C in the example illustrated 30 consists of a guided rod fitted with a cross member adapted for engaging the ends of the rods K_1 and K_2 . According to the arrangement in Fig. 2, the actuating device 35 may be elevated mechanically by a lever H pivoting about a fulcrum D and having its short arm beneath a track rail, whereby a slight depression of the rail under the weight of the train will produce an adequate elevation 40 of the actuating device C .

According to the modification illustrated 45 in Fig. 4, the movement of the lever H is produced by electro-magnetic means. An insulated rail section J_3 is inserted in the track and is connected with one terminal of a magnet coil m_5 , the other terminal of the latter being connected to the battery B which is grounded to the track rail as aforesaid. Consequently, the passage of a train over the crossing 50 will complete the circuit of the magnet m_5 which will then rock the lever H and elevate the actuating device C .

The battery B supplies current for the 55 various magnets and also for the warning signal S which is inserted in a circuit controlled by contacts carried by the rods K_1 and K_2 as hereinafter described.

The rod K_1 carries an upper laterally extending contact device which, when the rod 60 descends, bridges the gap between contacts 1 and 2. It also carries a lower contact device which, when the rod is up, bridges the gap between contacts 5 and 6 and when the rod is down as shown bridges the gap between 65 the contacts 9 and 10. The rod K_2 similarly

carries an upper contact device for bridging the gap between contacts 3 and 4 when this rod is down and a lower contact device for bridging contacts 7 and 8, when the rod is up, as shown, and for bridging the contacts 11 70 and 12 when the rod is down.

As will appear, the principal function of the actuating device C is to lift the rods K_1 and K_2 simultaneously whereupon they will be retained in the elevated position by the pawls or detents s_1 s_2 so long as the respective relay magnets remain unexcited. In Fig. 1 it must be assumed that one of the magnets m_1 or m_2 of the relay R_1 has been excited, thereby 75 attracting the armature r_1 and releasing the detent s_1 , so that the rod K_1 has been permitted to drop.

In effect, the relay devices start operations 80 from a definite combination of positions, for example dissimilar positions of the rods K_1 and K_2 as shown, and this combination is altered in definite sequence by the operation of the individual relay devices and of the common actuating device C . Each change in the 85 combination of positions causes a switching operation to be performed upon the controlled circuit and also the actuation of an individual device which in any combination of positions results in a new combination being produced, until finally, after the last circuit-making 90 device has been left, the position of rest is again arrived at in preparation for operation. Since in the present example the device located at the highway crossing effects a common 95 actuation, the condition of readiness for actuation must exist when the contact devices are in dissimilar positions. Thus it is always possible to re-convert the similar position of the contact rods resulting from the common actuation into a dissimilar position 100 by means of the actuating device located beyond the highway crossing N in the direction of travel. In detail the manner of operation of the arrangement is as follows:

If a train approaches the highway crossing 10 N from, for example, the direction of the rail section J_1 and traverses the insulated rail J_1 , it constitutes a connection between the terminal of the battery B connected to the non-insulated rails of the track and the armature of the relay R_1 . The latter is resting upon the contact 15 which is in electrical connection with the contact 9. In the bottom position of the contact rod K_1 illustrated in Fig. 1, said rod makes connection between the contacts 9 and 10 the latter of which is connected with one of the terminals of the electro-magnet m_3 of the relay R_2 , the other magnet terminal being connected to the other terminal of the battery B . By 12 the closure of the circuit described the armature of the relay R_2 is attracted, its locking pawl s_2 then releasing the contact rod K_2 until then retained in its upper position so that this rod K_2 now falls into the lower 13

position. In this manner a circuit is closed from the battery B through the signal device S, the contacts 1, 2 and 3, 4 of the contact rods K_1 and K_2 to the other pole of the battery B, a continuous signal being set in operation which is only interrupted when the train travels over the device C located in the immediate vicinity of the highway crossing N. As the train passes over the device C the lever H is set in vibratory motion due to the bending of the rails caused by the wheel pressure, the rod of the said device C and therewith the two contact rods K_1 , K_2 being thus elevated and the latter being locked in the upper position by the relay armatures r_1 , r_2 . The circuit for the signal current is thereby broken at the contacts 1, 2 and 3, 4 and the signal is put out of action. If, then, the train proceeding from the highway crossing N travels over the second insulated rail section J_2 , it connects the grounded terminal of the battery with the armature r_2 which rests on the contact 16. The path of the current is then through the contacts 8, 7, which are connected when the rod K_2 is in the upper position, to the magnet m_4 and thence to the other terminal of the battery. Due to the excitation of magnet m_4 the armature r_2 is attracted and the rod K_2 released so that it then drops to its lower position while the rod K_1 remains in its upper position. Thus the normal position is reproduced wherein the one contact rod is in the upper position and the other in the lower position, the positions of the rods K_1 , K_2 being now, however, reversed as compared with the positions illustrated in Fig. 1. Whereas when the first insulated rail section is passed over the contact between the current-carrying relay armature r_1 and the contact 15 is not interrupted by the switching operation, because the magnet m_3 of the relay R_2 is excited and not a magnet of the relay R_1 , on the other hand when the second insulated rail section J_2 is passed over, lifting of the armature r_2 of the relay R_2 away from the contact 16 is immediately initiated due to the excitation of the magnet m_4 of said relay. To prevent failure to operate under any circumstances the contact 14 is provided which makes connection with the armature r_2 immediately the latter has left the contact 16. A circuit is thereby closed from the grounded terminal of the battery, through the insulated rail section J_2 , armature r_2 , contact 14 and magnet m_4 to the other terminal of the battery, the magnet m_4 being thus maintained in a state of excitation until the last axle of the train has left the insulated rail section J_2 . The release of the pawl s_2 from the contact rod K_2 is therefore ensured in any case.

If, now, the next train approaches from the direction of the rail section J_2 precisely

similar switching operations take place in the manner described above.

The grounded battery terminal is then connected through the insulated rail section J_2 with the relay armature r_2 which rest on the contact 16 connected to the contact 12. In the lower position of the contact bar K_2 the contact 12 is connected with the contact 11 which is connected with one terminal of the electro-magnet m_2 of the relay R_1 . The other terminal of this electro-magnet m_2 is again connected to the other terminal of the battery B. The electro-magnet m_2 is then excited through the circuit described and the armature r_1 releases the contact bar K_1 , until then retained thereby in the upper position, so that both contact rods are then in the lower position and the signal-current circuit is closed. When the device C located in the vicinity of the highway crossing N is passed over both of the contact rods K_1 , K_2 are again brought into the upper position by the lever H and the rod of the device C, the signal being thereby put out of action. When next the insulated rail section J_1 is passed over a circuit is closed from the grounded battery terminal through the armature r_1 , the contact 15, the contacts 5, 6, connected when the rod K_1 is in the upper position, and the electro-magnet m_1 to the battery B; the contact bar K_1 is thereby released whereupon it drops and the position of the apparatus illustrated in Fig. 1 is resumed. In this action the contact 13 for the automatic retention of the relay R_1 in the excited condition plays exactly the same part as does the contact 14 of the relay R_2 .

If a train coming from the direction of the rail section J_2 encounters the switching apparatus in the position illustrated in Fig. 1, then the signal device is caused to function in precisely the same manner by a circuit which runs from the grounded terminal of the battery B through the un-insulated rails of the track and the axles of the vehicles to the insulated rail section J_2 and thence to the armature r_2 , the contact 16, the contacts 8, 7 connected in the position illustrated, and the magnet m_4 and from there back to the battery B. The armature r_2 is attracted and the contact rod K_2 thereby released; the latter then moves into its lower position in which the signal circuit from the battery B is closed through the signal device S and the contacts 1, 2, 3, 4 back to the battery. Simultaneously the armature r_2 closes a circuit through the contact 14 and the magnet m_4 to the battery B so that the relay R_2 remains locked in the excited condition until the last axle of the train has passed over the insulated rail section J_2 . When the highway crossing N is passed over both contact bars are returned into the upper position whereby the signal is put out of operation; then when the insulated rail section J_1 is traversed, the con-

tact bar K_1 , is brought, in the manner already described into its lower position so that the position of the apparatus illustrated in Fig. 1 is again arrived at.

The last of the possible cases of operation is that a train should come from the direction of the rail section J_1 , while the switching apparatus is in such a position that the rod K_1 is in its upper position and the rod K_2 is, on the other hand, in its lower position. The circuit is then from the battery B through the insulated rail section J_1 , the relay armature r , the contact 15, the contacts 5, 6, which are connected when the rod K_1 is in the upper position now assumed, and the electro-magnet m , to the battery B; the contact bar K_1 is released. Simultaneously the retaining circuit is, once more, closed through the armature r_1 , contact 13 and magnet m_1 , to the battery B which maintains the relay R_1 excited until the last axle of the train has passed over the insulated rail section J_1 . The closure of the signal-current circuit and its interruption by the return of the contact bars K_1, K_2 into the upper position when the highway crossing is passed does not differ in any way from the operations described above. When the insulating rail section J_2 is passed over, a circuit is made again from the same through the armature r_2 , the contacts 16, 8, 7, the electro-magnet m_2 and back to the battery; the contact bar K_2 is thereby released to return to the lower position and the retaining circuit for the relay R_2 is closed through the contact 14 and the magnet m_2 until the train has passed by.

It is therefore clear that the actuation of the signal, its putting out of action and the re-setting of the apparatus for the next train is ensured for every position of the switching apparatus and any direction of approach of the train, it being immaterial whether the direction of approach of the trains is alternated regularly or whether two or more trains pass over the safety apparatus successively in the same direction.

In cases in which operation without a battery is adopted magneto generators, which due to the vibration of the rails produce intermittent currents at shorter or longer intervals depending upon the speed of the train, are employed in place of the rail contacts or insulated rail sections J_1, J_2 connected with the battery B. It is then preferable to construct both relays like the relay R_2 in Fig. 3. The relay armature r_2 is provided with a glycerine dash-pot E or the like which allows of rapid elevation of the armature but only of slow descent of the same. The contacts 14, 16 are constructed as sliding contacts and are brought as close together as is allowable. The contact 16 is short whereas the contact 14 embraces on the contrary a large arc. Immediately a current impulse excites one of the electro-magnets, the arma-

ture passes from the contact 16 on to the contact 14. Even in the case of current impulses following one another very slowly, such as are caused by a slowly travelling train, the armature r_2 will with this arrangement, remain in its upper position on the contact 14 until the last axle of the train has passed the distant actuating device, since the sinking of the armature proceeds so slowly that a fresh impulse lifting the armature will have already arrived before a change in contact has occurred.

With vibratory magneto generators also absolutely reliable operation is ensured by this arrangement.

What I claim is:

1. Automatic warning signal for railway crossings and the like particularly for railways with one track only for up and down traffic, comprising in combination a signal apparatus, a control relay in connection with track means adapted for initiating a signal operation, and with track means adapted for cutting off such signal operation, and track means adapted for re-setting said relay control, said relay control comprising a plurality of contact devices adapted for individual operation in one phase and for common operation in another phase, the combination of positions determined for said contact devices by successive actuation of the track means being effective for the proper development of the signal switching operations substantially as set forth.

2. Automatic warning signal for railway crossings and the like comprising a track device at the crossing, two distant track devices one in each direction from the crossing, a control relay in connection with said track devices, a signal device under control of said relay, said control relay being first responsive to either one of said distant track devices for initiation of a signal operation, being next responsive to the track device at the crossing for cutting off said signal operation, and being finally responsive to the other one of said distant track devices for resetting substantially as set forth.

3. Electric relay and signal device for operation under control of track devices, comprising in combination duplex contact carriers, a signal circuit, actuating means operative under track control to displace said carriers simultaneously to break the signal circuit and make alternative relay circuits, self-locking means operative upon said carriers in the displaced condition, relay magnets operative upon said self-locking means and adapted to be energized under track control for the release of respective contact carriers, and relay magnet switches in operative association with said self-locking means substantially as set forth.

4. Electric relay for railway warning signal comprising two shiftable contact carriers

constantly tending to move to a position in which a signal circuit is made, an actuating device operative upon said carriers under track control for simultaneously displacing them to break said signal circuit, self-acting detents for engaging said carriers in the displaced position, relay magnets comprising armatures in operative connection with said detents, relay contacts engaged by said armatures, and terminals for connecting said armatures with distant track controls, said relay device being adapted for standing normally with one or other of its carriers displaced substantially as and for the purposes set forth.

5. Automatic signal for giving warning at a given place of train approach from a distance in either direction, comprising in combination a signal circuit, two shiftable contacts in said circuit, self-returning carriers for said contacts similarly displaceable from a signal-circuit closed position, track controlled actuating means disposed at the said place and operative for simultaneous displacement of said carriers, self-acting detents operative to retain said carriers in the displaced condition, armatures in operative connection with said detents, two relay magnet coils operative upon each armature, terminal contacts adapted to be engaged by said armatures, connections between said armatures and insulated track sections distant in either direction from the said place, and shiftable contacts on said carrier and in the circuits of said magnet coils substantially as and for the purpose set forth.

6. Automatic signal for giving warning at a given place of train approach from a distance in either direction along a single track, comprising in combination a duplex relay with self-setting elements and releasable locking means adapted for automatically retaining said elements when displaced from the self-set position, one element of said relay standing normally displaced in relation to the other similar element, two relay magnets in each element operative upon the respective locking means for effecting release thereof, the circuit of one magnet being made when the respective element is displaced and the circuit of the other magnet being made when the other element is self-set, distant electrical track controls adapted for completing the circuit of one or other of the magnets of the displaced element upon approach to said place of a train from either direction, track control means at said place operative upon the passage of the train for displacing the two elements simultaneously, said distant controls being further adapted for releasing one of the two displaced elements upon the passing of the train from said place, and a signal circuit opened by the displacement of one or both of the elements substantially as set forth.

7. Automatic warning signal for crossings

and the like on single track railways carrying up and down traffic comprising in combination two similar self-setting contact carriers, a movable striker adapted for simultaneous displacement of said carriers and rendered operative by the passage of a train over a track device at the crossing, automatic and releasable detents operative for retaining said carriers in the displaced condition, armatures in operative connection with said detents said armatures also combining the function of switch arms, two magnet coils operative upon each armature, sets of terminal contacts for said coils, contacts on said carriers adapted for engaging appropriate terminal contacts of said sets in the self-set condition of said carriers and other terminal contacts of said sets in the displaced condition of said carriers, distant track devices connected up for electrifying appropriate magnet circuits upon the passage of a train over said distant track devices in either direction of travel, the armatures engaging contacts and functioning as switch arms to preserve such connection whether in the on or off position, and a signal circuit which is made only when both carriers are self set, the terminal contact sets being so arranged that the circuit of one magnet coil operating an armature is made by the self-setting of the respective carrier and the circuit of the other coil operating the same armature is made by the displacement of the other carrier, whereby a train passing over either of the distant track devices will effect a release and self-setting of a displaced carrier substantially as set forth.

In testimony that I claim the foregoing as my invention, I have signed my name.

ALOIS FEYERTAG.
